FUSE CONSTRUCTION

William O. Schultz, South Milwaukee, Wis., assignor to Line Material Company, South Milwaukee, Wis., a corporation of Delaware

Original application May 24, 1934, Serial No. 727,250. Divided and this application August 4, 1939, Serial No. 288,445

3 Claims. (Cl. 200—114)

This invention relates to fuse constructions and is particularly directed to a drop-out type of fuse.

This application is a division of my copending application Serial No. 727,250 filed May 24, 1934, for Fuse construction.

Objects of this invention are to provide a novel form of fuse, such as the expulsion fuse type, in which the fuse tube operates first in the manner of an expulsion fuse, then moves downwardly and increases the gap in the circuit, and finally comes to rest projecting outwardly from the body portion so as to give a visual signal indicating that the fuse has blown.

In greater detail, objects of this invention are to provide a housed type of expulsion fuse in which the fuse tube is biased towards motion axially of the fuse tube and downwardly and outwardly from the housing and is normally restrained from such motion by the fuse link, the rupturing of the fuse link releasing the fuse tube and allowing such outwardly biased fuse tube to be projected downwardly and outwardly from the housing.

Further objects are to provide a construction in which the lower fastening means for the fuse link is so constructed that it tends to quickly withdraw whatever remains of the lower portion of the fuse link from the fuse tube, such action being also assisted by gas pressure generated within the fuse tube, so that the combination of these two features insures the extinguishing of the arc within the fuse tube in a much shorter time than with the usual type of expulsion fuse, the fuse tube itself subsequently sliding vertically downwardly and increasing the gap formed in the circuit.

Further objects are to provide a construction in which the downward motion of the fuse tube is facilitated, in which latching means are provided for normally holding the fuse tube in elevated position, and in which means are provided for positively releasing the latching means when the fuse link is ruptured thus insuring the release of the fuse tube.

An embodiment of the invention is shown in the accompanying drawing, in which:

The single view is a side elevation of the device with parts in vertical section, such view showing in dotted lines the final position of the fuse tube after the fuse link has been ruptured.

Referring to the figure, it will be seen that the housing 38 is provided with a door 39 pivoted adjacent its lower end in any suitable manner as by the pintle pin 40. The door and the housing

jointly provide an opening through which the lower end of the fuse tube projects. The housing is preferably cut away adjacent its lower portion and provided with side flanges 41 to provide space within which the rocking contact member 42 may move. This rocking contact member will be described in greater detail hereinafter.

The housing is provided with a baffle 43 and with an upper terminal member 44 and a lower terminal member 45. These members carry 10 spring arms or contact members 46 and 47 respectively, the member 47 engaging around the lower contact or sleeve-like cradle member 48, and the upper member engaging the upwardly tapered, conical end 49 of the nut for the upper 15 end of the fuse tube 50.

This conical or tapered portion 49 thus does not interfere with the free downward sliding motion of the fuse tube, although it is gripped between the spring arms 46. The upper end of the member 49 is positioned loosely within the aperture 51 of the clip 52 carried by the upper end of the door. This clip is provided with a downwardly turned portion 53 which fits between the converging spring arms 46 and thus serves to 25 releasably hold the upper end of the door closed even if the fuse tube is removed.

The door is provided with an abutment 54, against which the lower contact 48 bears. This lower contact is provided with a hook member 30 55 which engages over the strap or anchoring member 56 carried by the door. Springs 57 bear against the ears 58 carried by the contact 48 and thus hold the fuse tube to the door.

The fuse tube is provided with a lower sleeve 35 or member 59 which is equipped with rollers 60 engaged by the arms or hooks 61 of the rocking contact 42, such rocking contact being spring urged outwardly, as indicated, and being connected by means of a flexible conducting leader 40 62 to the contact 48. The latch arm 61 is urged toward a released position by spring 33' on pintle pin 32' on which the lever arm 61 is mounted.

It is to be noted, however, that the rocking contact 42 is provided with an extended lip 63, over the lower end of which the fuse link 64 passes, such link being preferably positioned within a slot formed in the lower portion of the lip 63, as indicated in the figure. The free end of the link 50 is clamped by means of the thumb nut 65. The rocking contact 42 is biased so as to tend to rock in a clockwise direction, as indicated by the arrow in the figure.

It is to be noted that the sleeve 59 in reality 55

constitutes a cuplike member, and that the lower contact member 48 or cradle not only acts in the manner of a sleeve to slidably hold the fuse tube, but jointly with the member 59 houses a compression spring 66 which urges the fuse tube downwardly, thus assisting the action of gravity. Spring 66, in addition to gravity, exerts a force reacting against latch arm 61.

10 The operation of the apparatus is as follows:

When the fuse blows, the fuse link is ruptured. The lower pivoted contact member 42 is released and swings in a clockwise direction, withdrawing the hook-like arms 61 from the rollers 60, thus releasing the fuse tube 50. The fuse tube drops 15 downwardly into the dotted line position and projects below the lower portion of the housing, thus greatly increasing the gap in the electrical circuit in addition to that provided by the ruptured fuse link.

20 It will be seen that this invention provides a novel form of housed type expulsion fuse in which not only expulsion action is obtained, but also in which the fuse tube moves vertically downwardly from the housing and thus increases 25 the gap in the electric circuit.

It will be seen further that the construction is simple, is easy to handle, that the fuses are easy to replace, and that the device is eminently practical.

30 Although this invention has been described in considerable detail, it is to be understood that such description is intended as illustrative rather than limiting, as the invention may be variously embodied and is to be interpreted as claimed.

35 I claim:

1. A fuse construction comprising a housing having an open bottom and having contacts, guiding means mounted within said housing, a fuse tube slidably supported within said guiding 40 means, a spring encircling said fuse tube and urging said fuse tube towards said open bottom, said fuse tube having spaced contacts normally electrically connected to said first mentioned

contacts, a fuse link electrically joining said spaced contacts, a lever for temporarily latching said fuse in operative and restraining position and movable toward a released position, said lever when in restraining position relieving said fuse link of excessive mechanical strain, and being constructed and arranged to be urged toward a released position when the fuse link is ruptured.

2. A fuse construction comprising a housing 10 having an open bottom and having contacts, guiding means mounted within said housing, a fuse tube slidably supported within said guiding means, a spring encircling said fuse tube and urging said fuse tube towards said open bottom, 15 said fuse tube having spaced contacts normally electrically connected to said first mentioned contacts, a fuse link electrically joining said spaced contacts, a lever for temporarily latching said fuse in operative and restraining position 20 and movable toward a released position, said lever when in restraining position relieving said fuse link of excessive mechanical strain, said spring also exerting a force reacting against said lever.

25 3. A circuit interrupting switch structure comprising a housing having an open bottom and having contacts, guiding means mounted within the housing, an arcing tube slidably supported within said guiding means, a spring encircling 30 said tube and urging said tube towards said open bottom, said tube having spaced contacts normally electrically connected to said first mentioned contacts, a flexible conductor in said tube electrically joining said spaced contacts, a lever for releasably latching said tube in operative position, said lever being movable toward a releasing position, and pulling said conductor from said tube when released, and current controlled means for releasing said lever under overload 35 conditions.

40 WILLIAM O. SCHULTZ.
